MEANS AND METHOD FOR MAKING
NECKTIES

Lillian L. King, Beverly Hills, Calif.

Application September 2, 1939, Serial No. 293,247

5 Claims. (Cl. 223—1)

My invention relates to the fabricating of neckties and is directed both to an improved method of making neckties and to means for performing the method.

5 While the general object of my invention is to produce quality neckties efficiently and expeditiously, the more special object of my invention is to produce such a necktie in a manner within the skill of the inexpert to the end that 10 first-grade ties may be made at home by persons of ordinary skill and experience.

Necktie material is cut on the bias, i. e., diagonally across the weave, not only for the diagonal effect in many of the patterns of fabric 15 used, but also and more important because a necktie of material cut diagonally and properly folded has the desired inherent tendency to hang flat and true. If the tie material that is cut on the bias is not folded correctly, however, 20 the bias of the weave becomes a stumbling block for the unskilled, developing strains in the finished tie that twist and distort the tie from the desired configuration and disposition on the wearer. Such a tie does not hang correctly.

25 The usual procedures of folding necktie blanks by eye or by dots marked on the material lead to difficulties, because, as I have discovered, in the first place, the fold lines are not often accurately perceived; in the second place, if accurately perceived are not accurately followed; and, in the third place, because the handling of 30 the material during the folding process develops strains and inaccuracies that are made permanent by the folding process itself to appear 35 promptly in the finished product.

To provide a simple foolproof manufacturing procedure that may be readily mastered by the unskilled and yet that precludes inaccuracy and distortion in the finished necktie, I have the following more specific objects characterizing my 40 invention: to hold the portion of the fabric that is to constitute the face of the finished tie immobile on a supporting surface during the folding of the tie blank, thereby avoiding handling 45 or straining of the most important portion of the tie blank; to fold longitudinal marginal portions of the blank successively from opposite sides of the blank toward said immobile portion; to provide guide means on said supporting surface 50 face to indicate accurately the required folds as well as the required sequence of the folds; to arrange such guide means to indicate the required successive configurations of the tie blank so that error arising at any stage of the folding process 55 becomes apparent immediately in some obvious

discrepancy between the instant configuration of the tie blank and the configuration indicated by the guide means; and to provide for maintaining the material of the finished face of the tie under tension in alignment with the bias of 5 the fabric throughout the folding process, thereby favoring the avoidance of lateral or torsion strains.

Other objects of my invention relate to the physical means for carrying out the preferred 10 practices contemplated. One of these objects is to provide simple and inexpensive equipment for guidance in the production of ties by the unskilled.

Another object is to provide a guide means for 15 practicing my invention efficiently and expeditiously on any number of successive tie blanks.

A still further of these objects is to provide a single such guide means that may be employed without confusion for folding a tie blank in more than one manner and for folding tie 20 blanks of different sizes.

Other objects and features of my invention will be apparent in the detailed description to 25 follow, taken with the accompanying drawing.

In the drawing:

Fig. 1 is a plan view of a pattern to indicate how yard goods may be cut on the bias to provide a tie blank in one practice of my invention; 30

Fig. 2 is a plan view of a tie blank assembled from pieces that are cut as shown in Fig. 1;

Fig. 3 is a plan view of a guide means employed in the preferred practice of my invention;

Fig. 4 is a plan view of the guide means of 35 Fig. 3 with a tie blank thereon, the tie blank being shown at an intermediate stage of the folding process;

Fig. 5 is a view similar to Fig. 4 showing the tie on the guide means at the final stage of the 40 folding procedure;

Fig. 6 is a cross-section of the necktie greatly enlarged taken as indicated by the line A—A of Fig. 5.

Fig. 7 is a view similar to Fig. 6 showing the 45 folds in a tie produced by a slight modification of the above procedure;

Fig. 8 is a plan view of a cutting pattern to indicate how material may be cut from yard goods to produce a smaller tie blank; 50

Fig. 9 is a plan view of the smaller tie blank assembled from pieces cut as indicated in Fig. 8;

Fig. 10 is a plan view of the smaller tie blank on the guide means of Fig. 3, the tie blank being shown at an early stage in the folding procedure; 55

Fig. 11 is similar to Fig. 10, the tie being shown in finished form; and

Fig. 12 is a cross-section of the tie greatly enlarged taken as indicated by the line B—B of Fig. 11.

In Fig. 1 I show a pattern 20 printed in the usual manner on tissue paper or the like. While any cutting layout may be employed in the practice of my invention, this particular pattern is of special economy in the use of material, since it permits me to cut cloth on the bias for two complete ties from one yard of cloth 24" wide. It will be noted that a diagonal line 21 divides the rectangle of the cutting pattern into two equal halves from each of which is obtained a relatively long piece of material 22 and a complementary relatively short piece of material 23, which pieces may be sewn together to make a single necktie blank. A necktie blank 25 so obtained is shown in Fig. 2, the blank having a transverse seam 26 at the juncture of the two pieces 22 and 23, and having its ends hemmed in the usual manner (not shown).

In Fig. 3 I show a guide means generally designated 28 to be employed in the fabrication of the necktie, the guide means being useful for assembling the two pieces 22 and 23 to make the blank 25 and being especially useful in subsequently folding the blank into the configuration of the finished necktie. Since the preferred form of my invention is embodied in a pattern set to be sold in department stores at relatively low cost for guidance in the home manufacture of ties, the guide means 28 may comprise a sheet of paper. In actual use after purchase the sheet of paper comprising the guide means 28 may be placed on a table for temporary service or may be permanently mounted on a relatively stiff backing, for example, as indicated in Fig. 3 a piece of heavy cardboard 29. In some practices of my invention the guide means may be mounted in this manner for sale to the trade or may comprise a relatively stiff sheet of suitable material suitably imprinted to serve my purpose.

The sheet comprising the guide means 28 has printed or otherwise marked thereon an outline 30 conforming accurately to the finished tie blank 25. To be sure that the two pieces 22 and 23 are properly sewn together to produce the desired configuration, the two pieces may be laid upon the guide means 29 to match the outline 30 in which disposition the two pieces will be caused by the outline to overlap at their junctures by the exact marginal portions required for the seam 26. By using the outline 30 in this manner I insure that the blank is assembled accurately and will closely conform to the outline.

Within the confines of the outline 30 are longitudinally disposed fold lines designated respectively by numerals 1—1, 2—2, 3—3, 4—4, and 5—5, which numerals indicate to the operator the sequence in which the fold lines are to be considered in the folding of the blank 25 into the configuration of a finished necktie. The fold lines are contracted in relative spacing toward the neck portion of the blank from both ends and preferably each of the fold lines is arcuate not only for the purpose of attaining a pleasing configuration, but also because I have discovered that curving the fold lines in the manner indicated in Fig. 3 tends to cause the finished tie to hang correctly.

Since the folds are made in the sequence of the numbers 1—1 to 5—5, it is apparent that the two fold lines 4—4 and 5—5 represent the configuration of the finished tie. It is character-

istic of my invention that throughout the folding process the portion of the tie blank that is to constitute the face of the finished tie lies undisturbed against the surface of the guide means throughout the various stages of the folding procedure. Since it is desirable for the sake of accuracy in the folding process to keep the central portion of the tie blank immobile between the fold lines 4—4 and 5—5, and since it is further desirable, as heretofore indicated, to maintain this central portion of the tie under longitudinal tension throughout the folding procedure, I anchor the central portion of the tie in place at the beginning of the folding procedure and release it only after the tie is folded to its finished configuration. In other words, after the pieces 22 and 23 are sewn together to form the blank 25, the blank is placed face down on the guide means 28 and is centrally anchored thereto under longitudinal tension. The anchoring of the tie blank may be accomplished, for example, simply by inserting pins 32 through the material of the blank 25 into the guide means 28 and the backing 29 of the guide means, the pins being placed at the opposite ends of the tie blank within the area defined by lines 4—4 and 5—5 with the cloth under slight tension. The tension should be sufficient to resist any incidental forces tending to move the cloth laterally relative to the guide means and should exceed the tension ordinarily placed on the material of the tie by its own weight when the tie is in use.

The initial fold is made along the line 1—1, the fold of the material being pressed down lightly with a heated iron. The disposition of the tie blank at this stage is shown in Fig. 4, the marginal portion of the blank that is folded over being designated 33. If the fold is accurately made, the tie blank after the initial fold will match the outline 30 as modified by the fold line 4—4. Since the material lies against this intermediate outline, any discrepancy between the intermediate tie configuration and the intermediate outline becomes apparent to the operator at once to indicate the need of correcting the fold. If it is apparent upon inspection that the first fold is accurate, the operator proceeds to make the second fold as indicated by the line 2—2, a heated iron being applied along the fold. Again the guide means 28 affords a check on the accuracy of the fold since the tie blank at the end of the second fold should match another intermediate outline defined by fold lines 1—1 and 2—2. The subsequent folds along the lines 3—3, 4—4, and 5—5 are made in the order given to result in the final configuration shown in Fig. 5, the operator being careful at each step to see that the instant configuration of the tie blank after each fold conforms to the corresponding intermediate outline defined by the proper fold line. Thus the necktie in course of the folding procedure is checked successively to match the following: initial outline 30 prior to the first fold; initial outline 30 as modified by line 1—1; the outline defined by lines 1—1 and 2—2; the outline defined by lines 2—2 and 3—3; the outline defined by lines 3—3 and 4—4; and the final outline defined by the lines 4—4 and 5—5.

If at the end of the folding procedure the final configuration of the tie conforms with the fold lines 4—4 and 5—5, the pins 32 are removed to release the folded tie and the tie is stitched in any suitable manner, usually by sewing together the overlapping folds at the rear side of the tie. Fig. 6 shows in cross-section the final

folded disposition of the material in a tie produced as described above.

In a second practice of my invention the above procedure is followed except that the fold along the line 1—1 is omitted. In other words, after the tie is anchored to the guide means the initial fold is made along the line 2—2 and the subsequent folds are made along the lines 3—3, 4—4, and 5—5 in sequence. The disposition of the 5 folds in the finished tie produced by this modified procedure is indicated in Fig. 7. The modified procedure may be regarded as preferable in that the resultant tie is more nearly uniform 10 in thickness. It will be noted that no liner or 15 filler material is necessary in either case.

In Fig. 8 I show a second cutting pattern 35 that may be used instead of the first cutting pattern 20 to produce a tie blank with less material. The arrangement of cutting lines in 20 Fig. 8 produces material for two ties from a piece of cloth 24" square. It will be noted that each of two halves of the square provides a relatively long piece of goods 36 for one end of the tie, a shorter piece 37 for the other end 25 of the tie, and a still shorter piece 38 for an intermediate portion of the tie. The tie blank generally designated 40 in Fig. 9 assembled from pieces 36, 37, and 38 is intended to match the 30 outline on the guide means 28 that is defined by the fold lines 1—1 and 2—2. In other words, in using the fold means 28 for fabricating a tie from the smaller blank 40, the operator disregards the marginal portions of the outline 30 lying outside of the fold lines 1—1 and 2—2. 35 To avoid confusion in using the two sizes of blanks, the marginal portions 41 of the outline 30 lying outside the lines 1—1 and 2—2 may be colored for contrast, as indicated by the cross-hatching in the various figures.

40 The pieces 36, 37, and 38 are preferably laid out on this inner outline for guidance in the matter of sewing them together to insure that the blank 40 is accurately assembled. The blank is then accurately matched with the inner outline 45 and the central longitudinal portion of the blank is suitably anchored at each end by pins 32 as previously described. The tie blank is then folded in sequence along the lines 3—3, 4—4, and 5—5 to the final configuration shown 50 in Fig. 11 defined by the fold lines 4—4 and 5—5. The tie produced by the blank 40, then, has the same configuration in plan as the tie produced from the blank 25, but as indicated by Fig. 12 has fewer folds. If desired, a liner 55 may be incorporated in the usual manner.

The specific forms of my invention herein disclosed in detail for the purpose of disclosure and to illustrate the principles involved will suggest to those skilled in the art various changes, modifications, and substitutions that do not depart 60 from my underlying concept, and I reserve the right to all such changes, modifications, and substitutions that properly come within the scope of my appended claims.

I claim as my invention:

1. The method of making a necktie from a necktie blank that includes the steps of: placing the blank face down on a supporting surface having guide lines representing the successive 5 folds to produce a finished necktie; temporarily attaching the blank to said supporting surface at the ends of the finished area of the blank; and while the blank is thus attached folding over and ironing successive longitudinal marginal portions of the blank along the successive fold lines visually indicated by said guide lines 10 on the supporting surface.

2. The method of making a necktie from a necktie blank that includes the steps of: placing the blank face down on a supporting surface having guide lines representing the successive 15 folds to produce a finished necktie; placing the blank under longitudinal tension over the central portion of the blank that is to constitute 20 the face of the finished necktie; securing the ends of the blank to maintain said tension during subsequent folding steps; and folding longitudinal marginal portions of the blank from 25 opposite sides along said successive guide lines to give the blank successive configurations matching the successive outlines defined by said guide lines.

3. A set of paper patterns for making neckties, including: a paper cutting pattern outlining a tie blank; and a paper fold guide providing an outline matching said tie blank and further providing a plurality of longitudinal fold 30 lines for the visual guidance of an operator in making the successive folds of a tie blank required for a finished necktie.

4. As a new article of manufacture means for guidance in the manufacture of neckties at home, said means comprising a flexible sheet having thereon the outline of a tie blank and a 40 plurality of longitudinal lines within said outline for visual guidance of an operator, said lines being at the locations of successive folds required to produce a finished necktie, two of said 45 lines defining the face of the finished necktie, said sheet being penetrable whereby a tie blank may be anchored on the sheet by pins through the sheet.

5. As a new article of manufacture means for guidance in the manufacture of neckties at 50 home, said means comprising a sheet of paper having thereon the outline of a tie blank and a plurality of longitudinal lines within said outline for visual guidance of an operator, said lines indicating the successive folds necessary 55 to produce a finished necktie, two of said lines defining the face of the finished necktie; and means to engage the opposite ends of the central portion of a necktie blank between said two lines to hold the central portion of the blank 60 in tension while the blank is being folded.

LILLIAN L. KING.
